US00D624017S

(12) **United States Design Patent**
Liu et al.

(10) **Patent No.:** **US D624,017 S**
(45) **Date of Patent:** **** Sep. 21, 2010**

(54) **BATTERY CONTACT**

(75) Inventors: **Yun-Xiang Liu**, Guang-Dong (CN);
Bing-Tao Yang, Guang-Dong (CN);
Yin-Lung Wu, Tu-Cheng (TW);
Ming-Chiang Chen, Tu-Cheng (TW)

(73) Assignee: **Cheng Uei Precision Industry Co., Ltd.**, Tu-Cheng, Taipei Hsien (TW)

(**) Term: **14 Years**

(21) Appl. No.: **29/357,824**

(22) Filed: **Mar. 17, 2010**

(51) LOC (9) Cl. **13-03**

(52) U.S. Cl. **D13/120**; D13/133; D13/154

(57) **CLAIM**

The ornamental design for a battery contact, as shown and described.

DESCRIPTION

FIG. 1 is a perspective view of a battery contact showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
